HYDRAULIC PUMP AND SYSTEM

Filed March 25, 1944

UNITED STATES PATENT OFFICE

2,504,606

HYDRAULIC PUMP AND SYSTEM

Warren R. Tucker, Dayton, Ohio, assignor to
H-P-M Development Corporation, Wilmington,
Del., a corporation of Delaware

Application March 25, 1944, Serial No. 528,059

5 Claims. (Cl. 103—37)

1

This invention relates to press systems, and in particular to systems for small presses such as laboratory presses.

The general arrangement of this invention comprises a double acting ram to which is supplied pressure fluid by a manually operated pump. The direction of reciprocation of the differential ram is determined by the operation of a three-way valve, the forward stroke being obtained by admitting pressure fluid to both sides of the differential ram, and the retraction stroke being obtained by exhausting the main area of the ram and supplying fluid to the retraction area.

The object of this invention is to obtain rapid closing, rapid opening and high pressure pressing by the ram.

It is an additional object of this invention to provide a multi-stage pump operable by a common actuating means and selectively operable as to each stage according to the position of the actuating means. It is therefore possible to get high speed action of a hydraulically actuated member such as a ram with relatively low pressure and then effect a reduced speed of the ram at increased pressure.

This invention will be more clearly understood upon reference to the following description and accompanying drawings in which:

Figure 1 is a diagrammatic lay-out of the press system,

Figure 2 is a longitudinal section through the manually operated pump,

Figure 3 is a transverse section through the pump and is indicated by the line 3—3 on Figure 2,

Figure 4 is a longitudinal section through the three-way valve.

Referring now to Figure 1, the differential pressure ram is indicated at 10 and is reciprocable within a cylinder 11. A manually operated pump at 12 supplies pressure fluid to a conduit 13 leading to the retraction area of the differential ram 10, and to a conduit 14 leading to a three-way valve 15 actuated by an adjustable handle mechanism 15a.

The three-way valve is connected, by means of a conduit 16, with the main area of the ram 10, and by means of the ports 17 with a reservoir indicated at 18. The three-way valve 15 is manually operable to close off the ports 17 while simultaneously interconnecting the conduits 14 and 16, or to close off the conduit 14 while simultaneously interconnecting the conduits 16 and ports 17.

Referring now to Figures 2 and 3, the construction of the pump 12 will be more clearly apparent. The pump comprises a casing 20 having therein a bore 21 which is shouldered as at 22. An inlet port at 23 serves to admit fluid to the interior of the pump casing, and an outlet port 24 serves as an exit for the pressure fluid from the pump casing. Check valves 23' and 24' are suitably located

in the ports 23 and 24 so as to prevent reverse flow therethrough.

Mounted within the bore 21 is a plunger 25 which is urged by means of a spring 25a to the left to engage the shoulder 22. Reciprocation of the plunger 25 within the bore 21 is effective to draw fluid in through the port 23 and to force it outwardly through the port 24. Reciprocation of the plunger 25 is brought about by oscillation of the shaft 26 and arm 27. The arm 27 is pinned to a yoke which abuts the piston 25, and has threaded therein the smaller diameter plunger 28.

It will be apparent that oscillation of the arm 27 to the right of center will be effective to move the plunger 25, and that oscillation of the arm to the left of center will be effective to reciprocate the plunger 28 independently of the plunger 25.

The pump is preferably mounted within the reservoir and the shaft 26 extends exteriorly thereof and has fastened thereto a handle 29, as shown in Figure 1.

Referring now to Figure 4, the construction of the three-way valve 15 is more clearly shown. This valve comprises a valve casing having three ports therein with which communicate the conduits 14, 16 and 17 as shown in Figure 4. A movable valve element 30 is reciprocated by means of the handle 15a and a threaded stem 32 to a right hand position to close off the port with which the conduit 14 communicates, or to a left hand position to close off the port with which the ports 17 communicate. In this way, the conduit 16 is connected selectively to the conduit 14 or to the ports 17.

As in the case of the pump, the valve 15 is preferably mounted within the reservoir with the handle 15a external thereof.

40

Operation

Assuming that the press is open, that is the ram 10 is in its downward position, a fast closing stroke is instituted by moving the valve member 30 of the valve 15 to the left to close off the ports 17. The operator then oscillates the handle 29 so as to reciprocate the plunger 25 within the bore 21, that is, the handle 29 is reciprocated to the right of its center position, as viewed in Figure 2. A rapid closing results from this and continues until the work ram 10 engages the work.

When the work ram 10 engages the work, pressure builds up within the cylinder 11 and in the pump casing 12 thereby making reciprocation of the plunger 25 more difficult. When the load on the plunger 25 becomes great enough to cause oscillation of the handle 29 to become difficult, the operator commences to oscillate the handle 29 to the left of center rather than to the right. This is effective to cause reciprocation of the small plunger 28 independently of the large plunger 25. The flow of fluid through the pump

20 is reduced and the pressure thereof is substantially increased. The working portion of the forward stroke is thus carried out at reduced speed and at increased pressure.

The work stroke of the ram 10 having been accomplished, the retraction stroke is accomplished by moving the valve member 30 to the right to close off the conduit 14 and to interconnect the conduits 16 and 17. Oscillation of the pump handle 29 will now cause fluid to be 10 delivered to the retraction area on top of the head 10a to retract the ram 10 within the cylinder 11.

The two-stage pump is of simple construction and provides means for obtaining a large volume 15 of flow at low pressure, or smaller volume of flow at higher pressures. The valve 15 is likewise of simple construction and provides a ready means of selecting between the forward and retraction stroke.

It will thus be seen that there has been provided a two-stage pump operable selectively by the same actuating means in order to produce different pressures and different speeds of delivery of the fluid. This is used in combination with the multi-way valve for controlling the direction of flow from the pump and both the pump and the valve are associated with a common reservoir for fluid that is used to actuate the ram and the ram itself is of the differential type.

It will be understood that a great variety of different constructions may be employed while still embodying the invention of this application as set forth in the specification and particularly as set forth in the hereinafter recited claims. While I have referred to a laboratory press it will be understood that this is only illustrative and this invention is applicable to a wide variety of structures of different sizes and uses.

Having thus fully described my invention what I claim as new and desire to secure by Letters Patent is:

1. A pump that includes in combination, a pump cylinder, piston means for producing flow through said cylinder, resilient means holding said piston means normally in an inoperative position, a second and smaller piston means reciprocable in said first piston means for also producing flow through said cylinder, and an actuating means directly connected with said second piston and having two selective positions of movement in one of which concomitant operation of both of said piston means is obtained and in the other of which operation of said second piston means only is obtained.

2. In a pump, a pump cylinder having a shouldered bore, a shoulder piston in said bore, a spring in said cylinder urging said piston in the direction to bring the shoulder thereof in engagement with the shoulder in said bore, a plunger extending through said piston, means connected with said plunger on the side of said piston opposite said spring for reciprocating said plunger, said means being adapted to abut said piston in a predetermined position, and a pivoted lever connected with said means whereby oscillation of said lever on one side of a predetermined line will produce reciprocation of said plunger and oscillation of said lever on the other side of a predetermined line will produce reciprocation of said piston and plunger in unison.

3. In a pump, a pump cylinder having a shouldered bore therein, a shouldered piston reciprocably mounted in said bore, a spring in said cyl-

inder urging said piston therein in a direction to bring the shoulder thereof in engagement with the shoulder in said bore, a plunger reciprocable through said piston, a block secured to said plunger on the side of said piston opposite said spring, said block being adapted for abutting said piston, inlet and outlet means for said cylinder, and a lever pivoted to said cylinder and connected with said block whereby oscillation of said lever on one side of a predetermined line will reciprocate said plunger alone and oscillation of said lever on the other side of said line will produce reciprocation of said plunger and piston in unison.

4. In a pump, a pump cylinder having a shouldered bore therein, a shouldered piston reciprocably mounted in said bore, a spring in said cylinder urging said piston therein in a direction to bring the shoulder thereof in engagement with the shoulder in said bore, a plunger reciprocable through said piston, a block secured to said plunger on the side of said piston opposite said spring, said block being adapted for abutting said piston, inlet and outlet means for said cylinder, a lever pivoted to said cylinder and connected with said block whereby oscillation of said lever on one side of a predetermined line will reciprocate said plunger alone and oscillation of said lever on the other side of said line will produce reciprocation of said plunger and piston in unison and resilient sealing means positioned between said plunger and piston and between said piston and cylinder.

5. In a pump, a pump cylinder having a shouldered bore therein, a shouldered piston reciprocably mounted in said bore, a spring in said cylinder urging said piston therein in a direction to bring the shoulder thereof in engagement with the shoulder in said bore, a plunger reciprocable through said piston, a block secured to said plunger on the side of said piston opposite said spring, said block being adapted for abutting said piston, inlet and outlet means for said cylinder, a lever pivoted to said cylinder and connected with said block whereby oscillation of said lever on one side of a predetermined line will reciprocate said plunger alone and oscillation of said lever on the other side of said line will produce reciprocation of said plunger and piston in unison, annular grooves around said plunger and around the outer periphery of said piston and annular resilient sealing members in said grooves for sealing between said plunger and piston and between said piston and cylinder.
